INCENDIARY BOMB AND FIRE
EXTINGUISHER

Harry Slatnick, Waterbury, Conn.

Application June 20, 1942, Serial No. 447,820

2 Claims. (Cl. 299—96)

This invention relates to incendiary bomb and fire extinguishers of a generally similar nature to that constituting the subject matter of my copending application Serial No. 440,358, filed on April 24, 1942, upon which the present apparatus constitutes an improvement.

An important object of the present invention is to provide, in an extinguisher of the character described comprising a tank for the reception of water and air under pressure, a novel construction and arrangement of foot actuated pump for storing compressed air in said tank.

Another very important object of the invention is to provide an extinguisher of the aforementioned character comprising a unique closure for the tank which will prevent leakage and which, in addition, will permit said tank to be expeditiously refilled.

Still another very important object of the invention is to provide an incendiary bomb and fire extinguisher comprising control valves and nozzles of a novel construction and arrangement.

Other objects of the invention are to provide an improved, portable incendiary bomb and fire extinguisher which will be comparatively simple in construction, strong, durable, highly efficient and reliable in use, light in weight, compact, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of an improved incendiary bomb and fire extinguisher constructed in accordance with the present invention.

Figure 2 is a top plan view of the device.

Figure 3 is a vertical sectional view, taken substantially on the line 3—3 of Figure 2.

Figure 4 is a vertical sectional view through the lower portion of the device, taken substantially on the line 4—4 of Figure 1.

Figure 5 is a detail view in vertical section through the upper portion of the filler neck.

Figure 6 is a view in vertical longitudinal section through one of the control valves.

Figure 7 is a view in vertical longitudinal section through the extensible spray tube.

Figure 8 is a view in vertical longitudinal section through one of the nozzles and the connection thereon of the extensible tube.

Figure 9 is a detail view in vertical section through the adjustable needle spray head.

Referring now to the drawings in detail, it will be seen that the embodiment of the invention which has been illustrated comprises a tank of suitable capacity and material which is designated generally by reference numeral 1. The tank 1 includes an elevated bottom 2 and a false bottom 3, thus providing upper and lower chambers 4 and 5, respectively, the former for the reception of water and air under pressure.

The lower compartment 5 in the tank 1 is for the reception of a foot operated pump 6. The pump 6 includes a base 7 which is firmly secured to the false bottom 3, said base projecting outwardly through a vertically elongated opening 8 which is provided therefor in the lower portion of the tank 1. A pump cylinder 9 is rockably mounted, as at 10, on one end portion of the base 7. A suitable piston 11 is mounted for reciprocation in the cylinder 9. The piston 11 is fixed on one end of a rod 12. Pivotedly mounted on the other end portion of the base 7 is a treadle or the like 13. The piston rod 12 is pivotally connected at 14 to the treadle 13. A spring 15 returns the treadle 13 to raised position. A flexible tube 16 connects the pump cylinder 9 to a valve 17 which depends from the bottom 2 for injecting air under pressure into the compartment 4 of the tank 1. Of course, the opening 8 also accommodates the foot of the operator which actuates the treadle 13.

The top 18 of the tank 1 has formed therein a filling opening 19. Mounted on the top 18 and rising therefrom is a filler neck 20 which encircles the opening 19. The filler neck 20 includes an internal base flange 21 which is secured to the top 18 and on which an annular sealing gasket 22 rests. As best seen in Figure 5 of the drawings, the filler neck 20 further includes an internal, downturned flange 23 on its upper end having diametrically opposite, inclined slots 24 therein. The neck 20 is for the reception of a removable closure 25 which is engageable on the resilient sealing gasket 22 for closing the opening 19. In the embodiment which has been shown, the closure 25 is substantially cup-shaped. Rigidly secured, as by riveting, on the closure 25 is a substantially U-shaped carrying handle 26. Journaled in the end portions of the handle 26 and in the closure 25 is a shaft 27 comprising protruding end portions which are flattened in a manner to form cams 28. A thumb lever 29 is fixed on the shaft 27. It may be well to here state that the cams 28 are adapted to pass
